UNITED STATES PATENT OFFICE.

VIRGIL H. MILLS, OF HUBBARD, TEXAS.

LAMP-BURNER.

1,073,358.

Specification of Letters Patent. Patented Sept. 16, 1913.

Application filed December 19, 1912. Serial No. 737,732.

To all whom it may concern:

Be it known that I, VIRGIL H. MILLS, a citizen of the United States, residing at Hubbard, in the county of Hill and State of Texas, have invented certain new and useful Improvements in Lamp-Burners, of which the following is a specification.

This invention relates to improvements in lamp burners, and one object of the invention is to provide a burner in which will be obtained a more perfect combustion than heretofore and in which the danger of explosion will be reduced to a minimum.

A further object of the invention is to provide means to assure the proper trimming of the wick, and a still further object is to provide an improved means for holding the chimney in position.

The several stated objects, and such other objects as will incidentally appear hereinafter, are attained in such a mechanism as is illustrated in the accompanying drawings, and the invention consists in certain novel features which will be hereinafter first fully described and then more particularly pointed out in the appended claims.

In the accompanying drawings: Figure 1 is an elevation of the lamp burner embodying my invention. Fig. 2 is a plan view of the same with the wick cone removed. Fig. 3 is a vertical section on the line 3—3 of Fig. 2. Fig. 4 is a detail section on the line 4—4 of Fig. 2. Fig. 5 is a detail perspective view of the trimming gage. Fig. 6 is a plan view showing a modification of the invention. Fig. 7 is a section on the line 7—7 of Fig. 6. Fig. 8 is a plan view showing a further modification. Fig. 9 is a section on the line 9—9 of Fig. 8. Fig. 10 is a detail perspective view of a portion of the chimney retaining ring.

In carrying out my present invention, I may employ a burner base 1 having the usual perforated draft plate 2, to which a wick cone 3 is hinged, as will be readily understood. Secured to the base 1, at intervals around the same, are spring fingers 4 having eyes 5 near their upper ends, through which a chimney retaining ring 6 is passed, as will be readily understood. The said ring 6 is usually constructed of spring wire having a hook 7 at one end and provided at its opposite end with an eye 8 adapted to engage said hook whereby the ring will be held coupled around the lamp chimney. Adjacent the eye 8 a spring coil

9 is formed in the ring, which coil is expanded to permit the engagement of the eye 8 over the hook 7 and then automatically retracts so as to hold the said parts 60 in engagement. To facilitate the manipulation of these elements, I provide a finger-piece or handle 10 at the end of this coil 9 so that, after the chimney is in place over the burner and upon the base 1, the ring 65 may be readily fastened by pressing the end thereof against the chimney and then with the fingers of the same hand drawing upon the said handle 10, so as to pull the eye 8 over and into engagement with the hook 7, 70 as will be understood. The operation of fastening the ring in position will thus be accomplished expeditiously and easily, with slight discomfort to the user and without any liability of breaking the lamp chimney. 75

At opposite sides of the wick tube 11, which extends up centrally through the base of the burner, I provide draft tubes 12 which are preferably extended at an angle from the upper end of the wick tube to and 80 through the base and open below the same at opposite sides thereof. These tubes terminate, as clearly shown, immediately adjacent the upper end of the wick tube and should be approximately of the same width 85 as the wick tube so that air rising through the said tubes will feed the entire body of the flame rising from the wick. The said draft tubes 12 being preferably disposed at an inclination or angle to the wick tube, 90 as shown most clearly in Fig. 3, any particles of soot or charred wick which might tend to drop upon the draft plate 2 will flow down through the said tubes 12 and consequently pass out from the burner without obstructing the draft therethrough and causing imperfect combustion. The tubes are rigidly secured in the base by being soldered or otherwise fixed to the draft plate and they may extend vertically, as shown at 100 13 in Figs. 8 and 9, in which event they would terminate above the wick raiser 14, as shown. A further embodiment of the invention would be the formation of a flange or box 15 upon the base plate around the 105 upper end of the wick tube, as shown in Figs. 6 and 7, which box would be open at its lower end so as to supply a strong current of air to the flame.

The wick 16 rises through the wick tube 11 and is raised or lowered to adjust the flame by the wick raiser 14 in the usual man-

ner. According to my present invention, however, the wick does not slide directly upon the walls of the wick tube, but passes through a gage or trimmer tube 17 which is slidably fitted within the wick tube. This gage or trimmer tube has secured to its lower end a lifter 18 which rises through the draft plate 2 and is provided at its upper end with a thumb piece 19 whereby it may be manipulated. This lifter 18 is preferably a resilient wire having bends 20 near its upper end which are adapted to engage the walls of the opening in the draft plate through which the lifter passes and thereby 15 retain the lifter, and the tube attached thereto, in either its raised or lowered position. The tube 17 is provided in its lower portion with one or more longitudinal slots 21 which accommodate the star wheels of the wick 20 raiser, so that neither element will interfere with the operation of the other. The upper end of the wick tube is curved, as shown clearly at 22, so as to form a gage when the wick is being trimmed to insure the proper 25 trimming.

It will be readily seen from the foregoing description, taken in connection with the accompanying drawings, that I have provided means for supplying a constant and 30 steady supply of air to the top of the wick so that proper combustion will be assured and the liability of explosions or of smoking the chimney will be reduced to a minimum. The air or draft tubes provided by 35 me, furthermore, serve to reinforce the base of the burner and may be secured to the upper end of the wick tube so as to effectually brace the same and thereby prevent the warping or twisting thereof, so that the appearance 40 of the lamp is improved. It is also essential to an economical consumption of oil and to obtain proper illumination from the lamp, that the wick be carefully trimmed and the smoking of lamp chimneys 45 is also very commonly due to improper or hasty trimming of the wick.

By my improvements the trimming of the wick in a proper manner is made certain, even though the trimming shears be manipulated by a mere novice and for this purpose I have provided the tube 17. When it is desired to trim the wick, the lifter 18 is manipulated to raise the gage or trimming tube 17, thereby drawing the wick up above the 50 burner and exposing the upper curved end of the trimmer tube. The shears are then manipulated and caused to bear upon the upper end of the trimmer tube while being manipulated, so that as a result the wick

is given the proper curved trim necessary 60 for proper combustion and efficient illumination.

The lamp burner embodying my improvements supplies sufficient air to the wick at the point of combustion to prevent overheating and the consequent explosion. Furthermore, should the lamp be upset or the oil be consumed prematurely, the supply of air furnished to the flame at an angle thereto, would extinguish the sputtering flame before any danger resulted.

Having thus described my invention, what I claim is:—

1. A lamp burner having a perforated base plate, a wick tube extending therethrough, and draft tubes extending through the base plates at opposite sides of the wick tube with their upper ends immediately adjacent the upper end of the wick tube to feed air directly to and laterally upon the upper 75 end of the wick.

2. In a lamp burner, the combination of a base, a wick tube extending therethrough, a gage tube slidably fitted within the wick tube, and a lifter attached to the said gage 85 tube and projecting above the base.

3. In a lamp burner, the combination of a base, a wick tube extending upwardly therefrom, and a gage tube slidably fitted within the wick tube and having its upper end 90 shaped to guide the trimming of the wick.

4. In a lamp burner, the combination of a base having a wick tube rising therefrom, a wick raiser co-acting with said tube, a gage tube slidably fitted within the wick tube and 95 constructed to accommodate the wick raiser, and means for raising and lowering the said gage tube.

5. In a lamp burner, the combination of a base having a wick tube rising therefrom, a gage tube fitted within the wick tube and longitudinally slotted, means for raising and lowering the said gage tube, and a wick raiser working through the slots in said tube 100 to engage the wick.

6. In a lamp burner, the combination of a base having a wick tube rising therefrom, a gage tube slidably fitted in the wick tube, means for raising and lowering the said gage tube, and draft tubes secured to the 110 base and arranged to deliver air at the upper end of the wick tube.

In testimony whereof I affix my signature in presence of two witnesses.

VIRGIL H. MILLS. [L.S.]
